CLAIM

The ornamental design for a stationary peg for a coal pulverizer, as shown and described.

DESCRIPTION

FIG. 1 is a perspective view of a stationary peg for a coal pulverizer according to a first representative embodiment of the present invention.

FIG. 2 is a top plan view of the stationary peg for a coal pulverizer shown in FIG. 1.

FIG. 3 is a side elevation view of the stationary peg for a coal pulverizer shown in FIG. 1; and,

FIG. 4 is a perspective view of a portion of the interior of the grinding section of a coal pulverizer, showing the stationary peg for a coal pulverizer shown in FIG. 1 in place within the grinding section.

The broken line showing is included for the purpose of illustrating environment and forms no part of the claimed design.
